UNITED STATES PATENT OFFICE.

ALEXANDER CLAPPERTON, OF YONKERS, NEW YORK.

PATTERN-MATCHING MECHANISM FOR LOOMS.

SPECIFICATION forming part of Letters Patent No. 596,039, dated December 21, 1897.

Application filed April 16, 1897. Serial No. 632,415. (No model.)

To all whom it may concern.

Be it known that I, ALEXANDER CLAPPERTON, a citizen of the United States, residing at Yonkers, county of Westchester, and State 5 of New York, have invented certain new and useful Improvements in Pattern-Matching Mechanism for Looms, fully described and represented in the following specification and the accompanying drawings, forming a part 10 of the same.

In the manufacture of fabrics consisting of a body formed by ground or body warp and weft threads and a pattern-surface formed by pattern-warp threads, such as pile fabrics 15 of the various classes, a serious difficulty arises from the fact that the pattern-warp is liable to run unevenly relatively to the ground or body warp, so that the successive blocks of the pattern formed by the pattern-warp are 20 long or short, while it is necessary that the successive pattern-blocks should be of the same length and register accurately with successive portions of the body-warp strands, so as to secure the uniform appearance of a 25 single breadth of the fabric and the matching of the pattern in successive breadths when placed side by side.

The object of the present invention is to provide means by which the proper uniform 30 length of the pattern-blocks and their accurate registry with different portions of the body of the fabric shall be secured and any irregularity therein automatically corrected by the action of the loom. I secure this re- 35 sult in accordance with the present invention by combining with the loom a reciprocating member controlled by the pattern-warp and acting to increase or decrease the tension and thus shorten or lengthen the pattern- 40 block in case the pattern runs long or short, and thus correct any irregularity in the pattern-registry. If the pattern-warp be taken up too rapidly in the pattern, as often happens, for instance, when a new spool of weft 45 is put in and this weft is coarser than that of the previous spool, the pattern-blocks will run too short, and this may be corrected by increasing the tension on the pattern-warp, while if the pattern-warp is taken up too 50 slowly in the pattern—for instance, when the weft on a new spool is finer than that of the previous spool—the pattern-blocks will run

too long, and this may be corrected by decreasing the tension on the pattern-warp.

In the preferred construction embodying 55 the present invention the taking up of the pattern-warp in the pattern and its let off by suitable let-off mechanism produces the movement of a reciprocating member, so that if the pattern-warp is taken up too rapidly 60 or too slowly the movement of the member acts through suitable mechanism to increase or decrease the tension, as required for correcting the pattern. This result may be secured by constructions of widely-different 65 forms; but I preferably employ as the reciprocating member a tension-bar over which the pattern-warp runs and which is weighted to produce the desired normal pressure on the warp, and combine with said bar springs 70 which act upon the bar so as to apply a yielding pressure, tending to move it in opposite directions, so as to increase tension upon the pattern-warp in case the bar moves too far in one direction on account of the warp being 75 taken up too rapidly and to support the bar and assist the strain of the pattern-warp and thus lessen the tension in case the bar moves too far in the opposite direction on account of the warp being taken up too slowly. 80

The broad features of the invention may be used with any suitable mechanism for securing the proper feed of the pattern-warp in conjunction with the reciprocating member controlling the tension of the pattern-warp as 85 it is taken up in the pattern, and such mechanism may be any suitable let-off acting upon the warp-beam or other suitable part. The pattern-warp, however, preferably passes to the tension-bar from the warp-beam over a 90 roller which holds the warp against slip and is rotated for letting off the warp to the tension-bar as required, and in the preferred form of my loom this roll controls another let-off acting on the pattern-warp beam, and this 95 double let-off mechanism forms a part of the invention in itself as well as in combination with the other features of the invention or with other suitable means coacting with this let-off mechanism to secure the proper matching of the pattern. 100

For a full understanding of the invention a detailed description of a construction embodying all the features of the invention in

their preferred form as applied to a pile-fab-
ric loom of a well-known class will now be
given in connection with the accompanying
drawings, forming a part of this specification,
5 in which—

Figure 1 is a diagrammatic side elevation
of the loom. Fig. 2 is an enlarged sectional
elevation of the feed-roller for the pattern-
warp and its actuating mechanism. Fig. 3 is
10 an enlarged side view of the let-off and match-
ing mechanism, the view being on the side of
the loom opposite that shown in Fig. 1. Fig.
15 4 is an enlarged vertical section, looking to
the right, on the line 4 of Fig. 1. Fig. 5 is a
section on the line 5 of Fig. 4. Fig. 6 is an
enlarged detail of the draw-off roller and its
feeding mechanism.

The loom to which my pattern-matching
mechanism is shown as applied is substan-
20 tially the same as looms now well known and
in common use in weaving tapestry carpets,
so that a full illustration and description of
this loom is unnecessary, it being understood
25 that the construction and operation of the
parts of the loom, aside from my novel mech-
anism, are or may be of any suitable form and
that the matching mechanism may be applied
30 to many other looms of the same class or of
other classes employing pile or similar pat-
tern-warps.

In the loom shown, A are the warp-beams
for the ground or body warp x, B the pile-
warp beam for the pile or pattern warp y, C
the heddles, D the lay, and E the breast-beam
35 over which the woven fabric passes to the
draw-off roll F and wind-up roll G, all these
parts and their actuating mechanisms being
of any common or suitable construction and
operated in any suitable manner, and the
40 loops in the pile-warp y, which form the pile
surface, being formed by pile-wires 1, which
are inserted and withdrawn by any suitable
pile-wire movement, all as will be readily un-
derstood by those skilled in the art, the draw-
45 off roll F being shown as operated by lever 10,
carrying pawl 2, engaging a ratchet on the
end of the draw-off roll.

Referring now to the parts in which the
present invention is embodied, the pile-warp
50 y passes from the warp-roll B downward over
a tension-bar, preferably a tension-roll a, the
bearings of which are mounted to move in
slots 12 in supports 13, and thence over a roll
b, having a roughened surface, so that the
55 pattern-warp will not slip on the surface of
the roll, but the roll b will positively draw it
forward as the roll is rotated by means pres-
ently to be described. From the roll b the
pile-warp passes to the heddles C over the
60 tension bar or roll c, which is carried by arms
11, mounted on studs at opposite ends of the
machine and connected at one end by arm 8
to the sleeve 9, mounted on the same stud as
arm 11 and carrying a forwardly-extending
65 arm d, on which is a weight e, adjustable in
position longitudinally of the arm, so as to se-
cure the desired normal pressure upon and

tension of the pile-warps y. The rear end of
this arm d is slotted or forked and moves upon
a vertical bar 14, between two springs f f', 70
coiled upon the bar. The tension-bar in the
construction shown is a smooth-faced bar, but
it may be a roll, if desired, and it will be un-
derstood that the location of this tension-bar
as shown is not essential and that it may be 75
placed in any other position and mounted in
any suitable manner so as to secure its proper
movement by the pile-warp. This tension-
bar c forms a reciprocating member by the
movement of which the matching mechanism 80
is controlled in the construction shown.

The shaft of roll b carries a ratchet-wheel
15, which is engaged by a pawl 16, carried by a
vertically-swinging pawl-lever 17, connected
by a link 18 to a lever 19, actuated to rotate the 85
roll b by a cam 20 and returned to position by
the spring 21. The roll b thus forms a part of
the let-off mechanism for the pile-warp and
acts to let off or feed intermittently the warp
drawn off the warp-beam B. The beam B is 90
directly actuated to let off the warp for the roll
b by let-off mechanism of any suitable form,
which is controlled by the rotation of the roll
b, through the movement of the tension-roll
a, this let-off mechanism being shown as of a 95
form common in such constructions, the novel
feature of this part of the construction con-
sisting in the control of this let-off. In the
let-off construction shown the warp-roll B car-
ries a gear 22 at one end, by which the roll is 100
rotated by a worm 23, carried by shaft 24, and
this shaft 24 carries a ratchet-wheel 25, which
is engaged by a spring-pressed pawl 3, car-
ried by a weighted pawl-lever 26, swinging on
shaft 24 and actuated by a slotted link 27, en-
gaging pin 4 on the lever, this link 27 con-
necting with a lever 28, actuated by a cam
29 to rotate the shaft 24 and returned by a
spring 30.

The control of this mechanism is secured 110
by an inwardly-projecting toe 5 on the lever
26, which is normally engaged by a swinging
catch 31, which is spring-pressed to throw it
toward the toe 5 by a coiled spring 6 on its
pivot, and is thus thrown into position to en-
gage the toe 5 at each feeding movement of
the weighted lever as actuated by the link 27.
This catch 31 carries a pin 7, which is engaged
by a trip-lever 32, pivoted at a fixed point on
support 33 and actuated by a link 34, con-
nected to the roll a, this lever 32, when its
outer end is raised by the upward movement
of roller a, acting on the pin 7 on catch 31 to
draw the catch back and release the toe 5 of
the lever 26. As will be seen from Fig. 4, 115
which shows the position of the parts with
the catch 31 engaging the toe 5, so as to hold
this part of the lever 26 depressed and the
other or actuating arm of the lever 26 raised,
the pin 4 is then held at the upper end of the 120
slot in the link 27, so that the upward move-
ment of the link 27 does not actuate the lever.
There is therefore no rotation of the shaft 24
by the pawl 3 as link 27 is raised, except

when the catch 31 is thrown out by the trip-lever 32, actuated by the upward movement of the roll *a*, and this upward movement of the roll *a* takes place only as it is moved to 5 the upper end of its slot by the drawing off of the pile-warp by roller *b* as the latter is rotated.

It is sometimes necessary to throw the draw-off roll *F* out of operation, and it is desirable 10 that when this is done the roll *b* shall be similarly thrown out of operation, so that the pile-warp will not be drawn off thereby, but the pile-warp held under proper tension during the stopping of the draw-off roll *F*. I have shown 15 a simple means for this purpose in which the pawl 2 for actuating the draw-off roll *F* is thrown out of engagement by a slotted arm 35 on a rock-shaft 36, having a handle-arm 37, so that by moving the latter to the left 20 the pawl 2 is thrown out of engagement with the ratchet on draw-off roll *F*, and this rock-shaft 36 carries an arm 38, which is connected by a link 39 to a lever 40, which as the pawl 2 is thrown out by the movement of handle- 25 arm 37 engages the pawl 16 and throws it out of position to engage the ratchet 15 on roll *b*, the levers 10 and 17 then moving idly without rotating either the draw-off roll *F* or the roll *b*. It will be understood that this de- 30 vice is not essential, but such means is preferably used and in itself forms a specific feature of the invention.

The operation is as follows: As the roll *b* is rotated intermittently by the cam 20 and 35 connections it draws off and feeds forward the desired amount of pile-warp, the tension upon which is preserved by the weighted arm *d* acting upon the tension-bar *c*, the arm *d* being lowered as the pile-warp is taken up in 40 the pattern, so that the forward end of the arm *d* plays up and down on the rod 14 between the springs *f* and *f'*. The slack in the pile-warp between the warp-beam *B* and roll *b* is taken up by the intermittent motion of 45 the roll *b*, which lets off less warp at each operation than the warp-beam and the roll *a* thus raised in the slots 12. When this roll *a* has been raised, so as to actuate the lever 32 to draw the catch 31 out of engagement with 50 the toe 5 on the pawl-lever 26, the weighted end of this lever withdraws the lever and pawl, so that the pin 4 is at the lower end of the slot in the link 27, and on the next movement of the link actuated by cam 29 the pawl-lever 26 is actuated to rotate the shaft 24 55 through ratchet 25 and thus rotate the roll *b* to let off the required amount of pile-warp which is taken up by the downward movement of the tension-roll *a* in the slots 12. 60 This downward movement of the roll actuates the lever 32 to release the pin 7 on catch 31, and the latter is thrown in by spring 6, so as to engage the toe 5 and thus hold the pawl-lever 26 out of position to be actuated by the 65 link 27 until the next upward movement of the roll *a* again releases the catch 31. If the pile-warp *y* is taken up too slowly or too rap-

idly in the fabric being woven and thus runs out of registry, so that the pattern-blocks are not of the proper length, the pattern-blocks 70 in the fabric will be too long if the pile-warp is taken up too slowly and the pattern-blocks will be too short if the pile-warp is taken up too rapidly. In correcting the registry, therefore, so that the pattern-blocks will be of the 75 same length the pattern will be shortened in the first case by decreasing the tension upon the pile-warp so that the warp will be taken up more rapidly by the pile-loops of the pattern and the pattern will be lengthened in 80 the second case by increasing the tension upon the pile-warp so as to draw the pile-loops more tightly. These results are secured by the forward end of the weighted arm *d* and the springs *f* *f'*, as follows: If the pattern runs short—that is, if the pile-warp is taken up more rapidly—the arm *d* will be raised by the taking up of the warp so as to move the forward end of the arm *d* into contact with and to press upon the upper spring 85 *f*, as it is obvious that this movement of the arm *d* depends upon the rapidity with which the pile-warp is taken up. As the forward end of the arm *d* comes into contact with and presses upon the spring *f* the resistance of 90 the weight *e* to the further movement of the arm *d* and the taking up of the pile-warp in the pattern is increased by the pressure upon the spring *f*, the spring securing a yielding or gradual increase of this pressure and thus 95 of the tension upon the pile-warp. This increase in tension acts to draw the pile-loops more tightly and thus to lengthen the pattern so as to correct the irregularity. If the pattern runs too long, the action is just the 100 reverse, the pile-warp being taken up more slowly and it being necessary to decrease the tension upon the pile-warp so as to shorten the pattern. This result is attained by the engagement of the arm *d* with the bottom 105 spring *f'* as the arm lowers under the excess of tension and slower taking up of the pile-warp, and the weight of the arm is thus supported in part by the spring and the tension upon the pile-warp thus gradually decreased, 110 115 so as to shorten the pattern and correct the irregularity.

In this class of looms it is frequently desirable to change the feed of the roller *b* for weaving different grades of material. This 120 may be done in the construction shown by increasing or decreasing the amount or frequency of movement of the roll *b*, which may readily be provided for by change-speed gearing between the ratchet-wheel 15 and roll *b*, 125 or other suitable means for varying the feed of the pattern-warp.

It will be understood that the invention is not to be limited to the construction shown, but that many modifications may be made 130 therein by those skilled in the art without departing from the invention.

What I claim is—

1. The combination with a loom, of a pat-

tern-matching mechanism provided with a member having a reciprocating movement controlled by the pattern-warp, and means controlled by the movement of said member for varying the rate at which the pattern-warp is taken up in the pattern for the correction of the pattern-registry, substantially as described.

2. The combination with a loom, of a pattern-matching mechanism having a member over which the pattern-warp passes, said member being moved in one direction by the warp as the warp is taken up in the pattern and moved in the opposite direction as the warp is let off, and means controlled by the movement of said member for varying the rate at which the warp is taken up in the pattern for the correction of the pattern-registry, substantially as described.

3. The combination with a loom, of a pattern-matching mechanism having a reciprocating member moved by the pattern-warp, and means controlled by said member for varying the tension of the pattern-warp for the correction of the pattern-registry, substantially as described.

4. The combination with a loom, of a pattern-matching mechanism having a tension-bar for the pattern-warp, and means controlled by the movement of said tension-bar for varying the tension of the pattern-warp for the correction of the pattern-registry, substantially as described.

5. The combination with a loom, of a pattern-matching mechanism having a reciprocating member moved by the pattern-warp and a spring opposing the movement of said member to vary the tension of the pattern-warp for the correction of the pattern-registry, substantially as described.

6. The combination with a loom, of a pattern-matching mechanism having a reciprocating member moved by the pattern-warp, and means for opposing and assisting the movement of said member to vary the tension of the pattern-warp for the correction of the pattern-registry, substantially as described.

7. The combination with a loom, of a pattern-matching mechanism having a tension-bar for the pattern-warp, and springs acting upon said bar to oppose and assist its movement by the pattern-warp and brought into action to vary the tension on excess of movement of the bar in either direction, substantially as described.

8. The combination with a loom, of a tension-bar for the pattern-warp, an arm carried by said bar, and springs between which said arm reciprocates as the pattern-warp is let off and taken up in the pattern and acting upon said arm to increase or decrease the pressure on the tension-bar on excess of movement of the arm in either direction, substantially as described.

9. The combination with a loom and its pattern-warp beam, of a roll over which the pattern-warp passes from the warp-beam and

adapted to hold the warp against slip, means for rotating said roll intermittently for the advance of the warp from said roll, and means controlled by the pattern-warp between said roll and the pattern to vary the tension of the pattern-warp for the correction of the pattern-registry, substantially as described.

10. The combination with a loom, and its pattern-warp beam of a roll over which the pattern-warp passes from the warp-beam and adapted to hold the warp against slip, a tension-bar over which the warp passes from said roll, means controlled by the movement of said tension-bar to vary the tension on the pattern-warp, means for rotating said roll intermittently for the advance of the warp from said roll, substantially as described.

11. The combination with a loom, its pattern-warp beam, and let-off mechanism therefor, of a roll over which the pattern-warp passes from the warp-beam and adapted to hold the warp against slip, a tension-bar over which the warp passes from said roll, means controlled by the movement of said tension-bar to vary the tension on the pattern-warp, means for rotating said roll intermittently for the advance of the warp from said roll, and means for controlling the warp-beam let-off by the movement of the roll, substantially as described.

12. The combination with a loom, its pattern-warp beam and let-off mechanism therefor, of a second intermittently-operating let-off device to which the warp passes from the beam, means controlled by the pattern-warp after it leaves said second let-off device to vary the tension on the pattern-warp for the correction of the pattern-registry, and means for controlling the warp-beam let-off by the action of said device, substantially as described.

13. The combination with a loom, its pattern-warp beam, and let-off mechanism therefor, of a second intermittently-operating let-off device to which the warp passes from the beam, a tension-bar over which the warp passes from said device, and means controlled by the movement of said tension-bar for varying the tension on the pattern-warp, substantially as described.

14. The combination with a loom, its pattern-warp beam, and let-off mechanism therefor, of a second intermittently-operating let-off device to which the warp passes from the beam, means controlled by the pattern-warp after it leaves said second let-off device to vary the tension on the pattern-warp for the correction of the pattern-registry, a tension-bar between the warp-beam and said let-off device, and means for controlling the warp-beam let-off by said tension-bar, substantially as described.

15. The combination with a loom, its pattern-matching mechanism, and warp-beam and let-off mechanism therefor, of a second intermittently-operating let-off device to which the warp passes from the warp-beam, and

means for controlling the warp-beam let-off mechanism by the action of said device, substantially as described.

16. The combination with a loom, its pattern-matching mechanism, and warp-beam and let-off mechanism therefor, of a second intermittently-operating let-off device to which the warp passes from the warp-beam, a tension-bar for the warp between the warp-beam and let-off device, and means for controlling the warp-beam let-off mechanism by the movement of the tension-bar, substantially as described.

17. The combination with a loom, its pattern-matching mechanism, and warp-beam and let-off mechanism therefor, of an intermittently-operated roll over which the warp passes from the warp-beam adapted to hold the warp against slip, a tension-bar between the roll and pattern-warp beam, and means for controlling the let-off by the movement of said tension-bar, substantially as described.

18. The combination with a loom, its pattern-matching mechanism, and warp-beam and let-off mechanism therefor, and a draw-off roll and actuating mechanism therefor, of an intermittently-operated let-off roll over which the warp passes from the warp-beam,

means for controlling the warp-beam let-off by the action of said roll, and connections for throwing the roll-actuating mechanism out of operation by the throwing out of operation of the draw-off roll, substantially as described.

19. The combination with beam B, and let-off mechanism therefor having pawl-lever 26 and means for actuating the same, of a catch 31 engaging said lever at the end of a let-off movement to hold it out of operative position, tension-roll a, and means actuated by said roll for tripping the catch for the let-off movement, substantially as described.

20. The combination with an intermittently-operated let-off, of tension-bar c, arm d moving with said bar, and springs f, f' on opposite sides of said arm, arranged to oppose and assist the movement of the arm by the warp to increase or decrease the warp-tension substantially as described.

In testimony whereof I have hereunto set my hand in the presence of two subscribing witnesses.

ALEXANDER CLAPPERTON.
